IGNACE MARTIN, OF NEWARK, NEW JERSEY.

Letters Patent No. 76,337, dated April 7, 1868.

IMPROVED BRICK-MACHINE.

The Schedule referred to in these Letters Patent and making part of the same.

TO ALL WHOM IT MAY CONCERN:

Be it known that I, IGNACE MARTIN, of Newark, Essex county, New Jersey, have invented a new and improved Brick-Machine; and I do hereby declare that the following is a full, clear, and exact description thereof, which will enable others skilled in the art to make and use the same, reference being had to the accompanying drawings, forming part of this specification, in which—

Figure 1 represents a front view, partly in section, of my improved brick-machine, the plane of section being indicated by the line $x x$, fig. 3.

Figure 2 is a rear elevation of the same.

Figure 3 is a side elevation of the same.

Similar letters of reference indicate corresponding parts.

This invention relates to a self-acting brick-machine, which is so constructed that the clay is placed into the moulds, which are formed in the circumference of a revolving wheel, and is then pressed into the required shape by means of plungers, which are also arranged in the rim of the said wheel, and which are forced against the clay into the moulds by an eccentric-cam or crank, arranged on a shaft in the wheel.

When pressed, the brick are ejected from the moulds by the plungers, and are thrown upon an endless apron, on which they are conveyed to the drying-room, or to any suitable place. The whole machine works automatically, all that is necessary to start it being to place the clay into the moulds, and to revolve the horizontal driving-shaft.

A represents a wheel, which consists of a rim, A, spokes, b, and a hub, a, the spokes being arranged on the rear side of the wheel, and which is mounted on a horizontal shaft, B, that has its bearings in a frame, C, of suitable construction. The rim A is made of wood, or any other suitable material. It is perforated with radial oblong holes c c, of which two and two are arranged near each other, they being only separated by a thin partition, d, as is clearly shown in fig. 3, and by dotted lines in fig. 1. The outer circumference of the rim A is flattened above each pair of moulds c c, and round between each such pair, as is clearly shown in fig. 1. The width of the wheel A is, of course, in accordance with the length of brick to be used. On the shaft B is mounted a gear-wheel, e, as shown. D is a horizontal shaft, which has its bearings in the frame C, and which is arranged above the shaft B, as shown. It is connected, by gear-wheels f f, with the horizontal driving-shaft E, which is provided with a fly-wheel, g, and which receives motion by a belt passing over a pulley, h, or otherwise. On the shaft D is mounted a toothed segment, i, which meshes into the gear-wheel e. Thus, as the driving-shaft revolves, the shaft D will be revolved, while the shaft B and its appendages receive intermittent rotary motion by the toothed segment, the wheel being turned in the direction of the arrow 1, fig. 1. F is a hopper or receptacle for the clay. It is arranged above the wheel A on one side of the shafts B D, and is open at the bottom, so that the clay can be pressed by any suitable mechanism into that pair of moulds c c, which is under it. The bottom of each mould is formed by a plunger, j, which fits tight in it, and which is provided with a stem, k, projecting toward the shaft B, as is clearly shown in figs. 1 and 2. The plungers of those moulds which are under the hopper are drawn in, i. e., they are as near to the inner circumference of the rim A as possible, as is indicated by dotted lines in fig. 1. The moulds are, therefore, perfectly open to receive as much clay as they can hold.

When a pair of the moulds are thus filled, the wheel will be turned by the segment i, and the filled moulds will be carried so as to be vertically above the shafts B and D. Above the rim of the wheel, vertically above the shaft B, is arranged a board or plate, G, which is capable of covering a pair of moulds. It is pressed upon the flattened part of the rim by two eccentric-shafts H H, which are hung in the frame C above the board G, and of which one is operated by a connecting-rod, l, which has a pin or roller at its lower end that fits into an eccentric-groove which is provided in the face of a disk, I, mounted on the shaft D, as is indicated in fig. 3. Oscillating motion is thus imparted to the one shaft H, which thereby is made to alternately press upon the board and raise the same, the latter being done by means of a hook, m, working under a pin, n, on the boards, as is clearly shown in fig. 2. One such hook should be mounted on either end of the shaft H, and a pin, n, be provided on either end of the board G, so that both ends of the board are raised simultaneously. The shafts

H H are connected by gear-wheel or toothed segments o o, fig. 2, so that they will move together. When the moulds are under the board G, the same is pressed down by the eccentrics H, so as to completely close the upper entrance of the moulds, and to sustain the upward pressure of the clay. The latter is then pressed by the plungers j into the required shape. The plungers are moved up by a sliding plate, p, which has a horizontal slot, through which a crank, q, which is attached to the shaft D, passes. During each revolution of the latter, the plate p will therefore be once raised and lowered by the said crank. The plate p slides in a stationary frame, r, fixed in the wheel, as seen in fig. 2. The upper edge of the plate fits under the lower end of the stems k k, and when raised by the crank, it raises the plungers in the moulds, and presses the clay.

While the brick are thus being pressed, it is necessary that the wheel A should remain perfectly stationary, and although it is not moved during the said process by the toothed segment, it may still be moved a little by some unforeseen causes, whereby a great strain would be placed upon the whole mechanism. To prevent any such shaking or other motion during the process of pressing the brick, I have provided a spring-catch, r, which fits into a notch, s, a series of the latter being provided in the inner circumference of the rim A. The catch r is pressed into that notch s which is directly above the shaft B, by a spiral spring, as shown in fig. 1.

As soon as the brick have been thus pressed in one pair of moulds, the spring-catch r is moved out of its notch by a cam, t, on the shaft D, around which it fits, (see fig. 1.) The pressure of the eccentrics H upon the board G is released, and the latter raised by means of the hooks m, and the plate p is lowered by the crank q. The wheel is then turned by the segment so that the next pair of moulds comes under the board G. Those moulds which contain the ready-pressed brick are carried from under the board G, and the brick in them are gradually pushed out the nearer they come to be vertically under the shaft. This is done by a stationary cam, J, which is arranged in the frame C, and under the stems k. As the wheel is turned, the stems k are gradually pushed out by this cam until, when the moulds are directly under the shaft B, the plungers will be pushed out as far as possible, and the brick ejected. They fall upon an endless apron, K, shown in fig. 1, and are thereby conveyed to any desired place. After the brick have been thus discharged, it is necessary that the plungers should be drawn in again to make room for another charge of clay from the hopper. For this purpose small pins or friction-rollers u u are secured to and project sidewise from the ends of the stems k.

L is a double or slotted stationary cam, through which the stems pass, and the inner edge of which forms a rest for the rollers u as the wheel is turned. The form of this cam is such that the plungers will be drawn in as soon as the moulds in which they are arranged arrive under the hopper again, as is clearly shown in the drawings. The plungers, however, are drawn in with difficulty unless lubricated. For that purpose I provide a trough, N, below the wheel A, containing oil, and in this I arrange a revolving brush, M, which takes up the oil from the trough, and applies it to the plungers before they are drawn back into the moulds by the action of the cam, as aforesaid. This shaft M, as well as that on which the apron is arranged, receives motion by means of belts, gear-wheels, or otherwise, from any one of the shafts arranged in or around this machine.

Having thus described my invention, what I claim as new, and desire to secure by Letters Patent, is—

1. The board or plate G, in combination with the eccentric-shafts H H, hooks m, and pins n, all made and operating substantially as herein shown and described.
2. The mould-wheel A, when provided with notches s s, in combination with the spring-catch r and cam t, all made and operating substantially as and for the purpose herein shown and described.
3. The trough N, as a receptacle for oil, and a brush, M, arranged to revolve therein, and contiguous with the plungers, to lubricate them, as specified, when arranged beneath and operating in combination with the revolving mould-wheel A, and secured to the base-plate C, substantially as described and shown.
4. The combination, with the wheel A, of the plate G and eccentrics H, of the plungers j, stems k, and cam p, all made and operating as set forth.
